UNITED STATES PATENT OFFICE

168,201

RECESSED BED CABINET

Rose A. Weiss, Miami Beach, Fla.

Application December 8, 1951, Serial No. 17,656

Term of patent 3½ years

(Cl. D33—19)

To all whom it may concern:

Be it known that I, Rose A. Weiss, a citizen of the United States, residing at Miami Beach, in the county of Dade and State of Florida, have invented a new, original, and ornamental Design for a Recessed Bed Cabinet, of which the following is a specification, reference being had to the accompanying drawing, forming a part hereof.

The figure is a perspective view of a recessed bed cabinet showing my new design, wherein the side of the cabinet not shown is similar to that shown, while the back is plain.

I claim:

The ornamental design for a recessed bed cabinet, substantially as shown and described.

ROSE A. WEISS.
